(57) **CLAIM**

The ornamental design for a solar powered controller, as shown and described.

DESCRIPTION

FIG. 1 is a front perspective view of the solar powered controller.

FIG. 2 is a left side view of the solar powered controller which is identical to a right side view of the solar powered controller.

FIG. 3 is a front view of the solar powered controller which is identical to a rear view of the solar powered controller.

FIG. 4 is a top view of the solar powered controller; and,

FIG. 5 is a bottom view of the solar powered controller. The broken lines shown represent unclaimed subject matter and form no part of the claimed design.
